(57) **CLAIM**

The ornamental design for a module for exhibiting products in a point of sale, as shown and described.

DESCRIPTION

FIG. 1 is a perspective view of a module for exhibiting products in a point of sale according to our new design showing a lower extrusion of the module;

FIG. 2 is a front view thereof showing the module in a slightly tilted position;

FIG. 3 is a cross-sectional view cut along lines 3-3 in FIG. 2; FIG. 4 is an exploded perspective view of the module for exhibiting products in a point of sale, wherein the structure includes a cap and an interchangeable module; and, FIG. 5 is a perspective view of the module for exhibiting products in a point of sale according to our new design showing an upper extrusion of the module.

The broken lines shown in FIG. 4 are included for the purpose of illustrating the environment of the article and form no part of the claimed design.
